UNITED STATES PATENT OFFICE.

ARTHUR C. GAYNOR, OF STRATFORD, AND EDWIN G. GAYNOR, OF FAIRFIELD, CONNECTICUT.

ELECTRIC CONNECTER.

Application filed October 6, 1926. Serial No. 139,774.

Our present invention relates to electric connectors and more particularly to attachment plug caps used with two-part separable plugs. The invention also relates to improvements in contact blades or jacks suitable for use in connectors of this type, or for general use; to the arrangement and mounting of the connector blades, and to improvements in the construction of the connector as a whole.

Heretofore the commercial types of attachment plug caps or similar connectors have been constructed of a body of porcelain, or of molded insulating composition, provided with a pair of contact blades or jacks mounted on, and projecting from, the contact face of the body. The body of insulating material has usually been provided with a central opening or passage through which the wires to be connected to the contact blades enter, and these wires are then connected to the contact blades by means of binding screws about which a length of the wire, from which the insulation has been removed, is wound and then clamped by the head of the screw.

Connecters or attachment plug caps constructed in this manner, however, have a number of disadvantages. The winding of a length of wire about the binding screw and clamping it tightly is not only a laborious and troublesome manipulation, but also necessitates the use of a length of wire to secure a proper anchorage. The use of this extra quantity of wire involves a considerable expense when the plugs or connectors are made in large quantities. Moreover, the contact between the wire and the binding screw element is a rigid one and is unable to accommodate any displacement of the wire so that a very slight variation in the position or dimensions of the wire or binding elements will impair the contact even though the connection is still maintained. In the usual construction of plug caps, it is at times difficult to grasp the surface of the cap, as when the plug is inserted in a shade or other deep narrow recess, and there is a tendency to pull on the connecting wires rather than on the cap. This tends to loosen the contact between the wire and the terminals or binding screws, thus impairing the contact and the electrical conductivity therethrough.

Our present invention obviates these vari-

ous disadvantages, one of its objects being to provide a body of insulating material of molded or stamped construction, in which the contact blades may be mounted and which may be easily and quickly inserted and held in an enclosing shell.

Another object of the invention is to provide a contact blade in which the end of a wire may be secured and resiliently grasped so as to exert a pressure on the wire at all times, regardless of any displacement of the wire.

A further object of the invention is to provide an attachment plug cap in which the lead wires are secured to contact blades at a face of a supporting insulating plate within an enclosing shell having a portion that may be easily grasped and in which any pull exerted on the lead wires is received and taken up on the insulating plate.

Still further features and objects of the invention are to provide an attachment plug cap or connector having a shell into which an insulating plate may be easily and quickly inserted and automatically locked as it reaches its proper position in the shell; to provide an insulating plate in which the contact blades may be mounted and the terminals of the wires may be secured thereto by a single manipulation; to provide an insulating body adapted to receive and separate the wires, to avoid all danger of short circuiting, and to take up any tension on the lead wires; to provide a plug cap having a projecting, gripping surface about the connecting wires; to provide contact blades of a double and a hollow construction having increased lightness and resiliency; to provide a mounting for a resilient blade of this type whereby the blade may be mounted and a wire be secured and gripped with a resilient pressure in a single operation and to a general improvement in the construction of connectors.

With these and other objects in view, which will further appear in the following detailed description, the invention comprises the various devices described in the following specification and claims.

The various features of the invention are illustrated in the accompanying drawing, in which the same reference character indicates the same part in the several views and in which:

Fig. 1 is a longitudinal view, largely in

section, through a plug and a cap embodying the preferred form of the invention,

Fig. 2 is a cross section of the cap taken on line 2—2 of Fig. 1,

Fig. 3 is a longitudinal section of the cap taken on line 3—3 of Fig. 2,

Fig. 4 is a longitudinal section of the cap taken through the axis of the cap at right angles to the view of Fig. 3, and showing one of the contact blades partly removed to illustrate the manner of inserting the wire,

Fig. 5 is a top plan view of an insulating plate forming part of the plug cap,

Fig. 6 is a bottom view of the insulating plate shown in Fig. 5,

Fig. 7 is a bottom view of a shell in which may be mounted the insulating plate shown in Figs. 5 and 6,

Fig. 8 is a cross sectional view of a terminal blade taken on line 8—8 of Fig. 4, and,

Fig. 9 is a top plan view of a terminal blade illustrating the manner in which the end of a wire is inserted and gripped.

25. In our present invention the contact blades are mounted in a circular plate of insulating material and extend from one face, which is enclosed in a shell, through openings in the plate and project from the opposite 30 exposed surface of the plate. The terminal ends of the lead wires are secured to the binding ends of the contact blades and the blades inserted through the openings in the insulating plate and thus mounted therein 35 in a single operation. In this operation the end of the wire is first passed through an opening in the blade, the blade is then inserted through an opening in the insulating plate, and as the blade is pushed into posi-

40. tion in the opening the wire is bent, received in a recess in the insulating plate and tightly gripped by the end of the blades, which are compressed with spring pressure about the wire. Before being thus gripped into the

45. terminal ends of the contact blades, the wire is passed through an opening in an enclosing shell and then through an open end of the shell. The edge of this open end is curled or turned inwardly in portions of its periphery to form retaining lips. The plate of

50. insulating material has portions of its periphery correspondingly cut inwardly so that it may be pushed inwardly past the retaining lips, and when entirely within the shell, it is given a turn to bring the uncut portions of its periphery underneath the retaining lips. The periphery of the insulating plate is notched and the wall of the shell indented so that when the proper position

55. is reached they interlock and prevent displacement. The portions of the lead wire within the shell are laid in separate grooves which hold them apart and insure against short circuiting. These grooves are also so 60. curved as to take up any tension on the wires.

Referring more particularly to the accompanying drawings, a pair of contact blades 10 and 11 are adapted to be inserted in spaced relation through openings 12 and 13 in an insulating plate 14. These contact blades may be arranged either in parallel or tandem being shown in parallel in the accompanying drawings by way of example. The blades 10 and 11 are similar in construction and but one of them will be described, it being understood that this description will apply to either blade.

Each blade is formed of a strip of metal bent to form a bight portion 15 and a pair of legs 16 and 17 which when removed from the opening 13 or 14, tend to diverge slightly as shown in Fig. 4, but when inserted in the opening 12 or 13 are compressed to a substantially parallel position. When the blade is inserted in its respective opening 13 or 14, the bight portion 15 forms the projecting end of the blade. The upper ends of the legs which are mounted in the openings 12 and 13 are bent to enable them to grip and hold the end of a lead wire. For this purpose the upper end of the leg 16 is bent sidewise to form a foot 18 and the upper end of the leg 17 is bent first outwardly in a direction opposite to that of the foot 18 to form a projection 19, then in a reverse curve 20 and is then extended in an extension 21 overlying and slightly spaced from, the foot 18. The curved portion 20 forms a spring which holds the extension 21 downwardly with a resilient spring action toward the foot 18 when the legs are pressed together which serves to press tightly a wire positioned between the foot 18 and the extension 21.

105. In securing a wire 22 or 23 of a cable 24 to a contact blade 10 or 11, a portion 25 of the wire is stripped of its insulation and inserted into an opening 26 in the leg 16 slightly below the foot 18. The wire is inserted from the inner side of the leg as indicated in Fig. 4 leaving a short projecting end 27 extending outwardly from the opening 26. The wire is then bent in the direction of the arrow in Fig. 9 to the position

110. shown in broken lines in Fig. 4. The blade is then pushed downwardly through its opening 12 or 13 whereby the legs 16 and 17 are pressed together and the extension 21 of leg 17 is pushed over the foot 18 of leg 16 and tightly presses the wire between. This pressure is always maintained, regardless of the thickness of the wire or any changes in this diameter and readily accommodates any thickness of wire. As the blade reaches the downward limit of its movement the projecting end 27 of the wire 22 is received in a deep narrow recess 28 extending sidewise of the upper end of the opening 12 or 13 and is thereby further bent and compressed as indicated in Fig. 1, and

thereby provides further anchorage to its respective blade. The foot 18 and the foot elements 19 and 21 are received in a broad shallow recess 29, which serves as a stop for 5 the blades, the upper surface of the extension 21 lying immediately beneath the upper surface of the plate 12.

The leg portions 16 and 17 of the blade may be of any desired construction or form, 10 but it is preferred to make them of rather thin metal and to curve their edge portions at 30 and 31 as indicated in Fig. 8, as this permits the necessary rigidity to be obtained with a thinner metal, than if the legs were 15 flat and, moreover, give a resiliency which enables a tighter or more permanent fit to be obtained in mounting the legs in their mounting openings 12 or 13. The breadth and thickness of the leg portions are normally slightly greater than those of the 20 openings 12 and 13, which are rectangular so that the blades are slightly compressed and exert a spring action against the edges of the holes.

25 To prevent sidewise displacement of the wire portion 25, the side edges of the extension 21 of leg 17 are turned downwardly to form short ledges 32.

The blades 10 and 11 having been inserted 30 in the holes 12 and 13 are prevented from being pushed back out of their openings by means of a plate of insulating material 33 which fits against the upper face of the plate 14. The plates 14 and 33 are held in 35 assembled position by means of a shell 34 having an open end into which the plates are pushed until the plate 33 reaches and rests against an inturned top or shoulder 35. When inserted in the shell 34, the plates 14 40 and 33 are entirely inclosed except for the face 36 of the plate 14 from which the blades 10 and 11 project. The shell 34 is extended beyond the shoulder 35 to form a neck 37 encircling the cable 24 and having at its 45 upper end an opening 38 through which the cable enters. The outer surface of the neck 37 is knurled at 39 to enable it to be readily grasped. This neck portion not only provides a gripping surface that permits the 50 cap to be grasped when mounted within an ornamental shade or bell but also provides a space within which frayed ends of the cord 24 may be retained.

In assembling the plug cap the cable is inserted through the opening 38 and through 55 the opening 40 in the plate 33. The wires 22 and 23 are separated for a short distance and the end portions stripped of insulation. The stripped portions are then secured to 60 their respective contact blades in the manner described above. The separate portions of the wire are then placed in the grooves or channels 41 and 42 on the inner face of the plate 14. These channels are so shaped as 65 to bring the wires in separate paths to the

center of the plate, thereby keeping the wires separated and taking up by a snubbing action any pull or tension on the cable or cord 24. The insulating plate 33 is then placed on the blade 14, closing the channels 41 and 42 and the plates 33 and 14 are pushed inwardly through the open end of the shell 34.

The shell 34 is provided with a pair of diametrically opposite retaining lips 43 and 44 projecting inwardly from the side edges of the shell 34. Each of these lips preferably extends around one quarter of the circumference of the shell opening. Between the ends of these lips a pair of free or cut-away portions 45 and 46 are left of substantially the full diameter of the shell. The edge of the plate 14 in two diametrically opposite portions 47 and 48 of approximately 90° each extend to a diameter substantially equal to that of the inner surface of the shell 34, and in a pair of intermediate portions 49 and 50 is cut-away or reduced to enable the plate to be moved past the retaining lips 43 and 44. In assembling the 90 plates and shell, the reduced portions 49 and 50 are brought into alignment with the lips 43 and 44, the plate 14 is pushed into the shell until a shoulder 51 on the edge of the plate rests against a shoulder 52 of the shell 95 and the outer face 36 lies entirely within the shell. The plate 14 is then given a quarter turn bringing the portions 47 and 48 in alignment with, and within the retaining lips 43 and 44, whereby the plate is retained within the shell. When the portions 47 and 48 are correctly aligned within the lips 43 and 44, an indentation 53 in the shell 34 projects into a notch 54 in the side of the plate 14 and thus holds the plate against 100 accidental rotation in the shell.

The plug cap thus formed may be used with any suitable receptacle or plug such as that indicated by way of example in Fig. 1. In this instance the blades 10 and 11 are 110 adapted to project into recesses 55 and 56, in a plug 57 and to contact with spring contacts 58 and 59 therein, one of these contacts being connected to an end plate 60 and the other to a screw shell 61. The legs 16 115 and 17 of the blades 10 and 11 may be provided with indentations 62 to receive corresponding indentation 63 of the spring contacts 58 and 59.

The invention described above provides a 120 cap and blade arrangement in which the wires may be secured to the blades and the blades mounted in an insulating body in a single manipulation. Moreover, the wires are held in the blades by spring contact 125 which insures an effective contact under all conditions. The length of wire required to enter the cap and be secured to the blades is reduced to a minimum, and the separated wires are held in separate paths that insure 130

complete insulation of any stripped portions. Any tension on these wires is taken up in the insulating body and is not transmitted fully to the contact blade members. The gripping neck 37 not only provides a portion that may be easily gripped when the plug is inserted into ornamental bells or shades or deep recesses and thus removes the occasion for pulling the wire, but it also provides a chamber for receiving unsightly frayed ends of the cable insulation. The interlocking arrangement between the plate 14 and the shell 34 provides an arrangement whereby the parts may be quickly and easily assembled and held in assembled position. It will be apparent that although the contact blades described above are particularly adapted for use in the cap construction described, they may be advantageously applied to other similar uses and also that other features of the invention might be used with blades of somewhat different construction.

As changes of construction could be made within the scope of our invention, it is intended that all matter contained in the above description or shown in the accompanying drawing shall be interpreted as illustrative and not in a limiting sense.

Having now described our invention, what we claim as new and desire to secure by Letters Patent is:

1. A contact blade having a bight portion, a pair of legs extending from said bight, each of said legs having a foot portion, one of said legs having an opening near its foot, the foot of said other leg being resiliently held slightly spaced from the end of said first leg when said legs are pressed together.
2. A contact blade having a bight portion, a pair of legs extending from said bight portion, one of said legs having a foot extending sidewise, and the other leg having a foot member extending first in a direction opposite that of said first mentioned foot, then curving through an arc and extending in spaced relation to said first mentioned foot when said legs are pressed together.
3. A connector of the type described which comprises a shell having an open end, an

insulating plate removably mounted in said open end, a pair of contact blades extending through said plate and projecting in spaced relation from the outer face of said plate, the inner face of said plate having a pair of curved grooves extending from the inner ends of said contact blades towards the center of said plate, and a retaining plate of insulating material on the inner face of said insulating plate and having a central opening communicating with said curved grooves.

4. A connector of the type described which comprises a plate having a pair of spaced openings and recesses at the inner face of said plate about said opening, a pair of contact blades, one for each opening, each of said contact blades comprising a pair of legs joined at the projecting end and extending through said opening, and having members within said recesses adapted to grip and anchor the terminal of a wire.

5. A connector of the type described which comprises an open ended shell, an insulating plate having one face enclosed in said shell and a pair of spaced openings through said plate, recesses in the enclosed face of said plate about said openings, and a pair of contact blades, one extending through each opening and projecting from the exposed face of said plate, and wire clamping elements on the inner ends of said blades within said recesses.

6. A connector of the type described which comprises an open ended shell, an insulating plate having one face enclosed within said shell, a pair of spaced openings through said plate, recesses in the enclosed face of said plate about said openings, a pair of contact blades, one extending through each opening and projecting from the exposed face of said plate, wire clamping elements on the inner ends of said blades within said recesses, and a plate of insulating material enclosed between said inner face of said plate and the inner wall of said shell.

In testimony whereof we hereunto affix our signatures.

ARTHUR C. GAYNOR.
EDWIN G. GAYNOR.
